UNITED STATES PATENT OFFICE

151,162

DESIGN FOR A TABLE

Jerome L. Metz, Chicago, Ill., assignor to J. L. Metz Furniture Company, Hammond, Ind., a corporation of Illinois

Application April 17, 1947, Serial No. 138,454

Term of patent 7 years

(Cl. D33—14)

To all whom it may concern:

Be it known that I, Jerome L. Metz, a citizen of the United States, residing at Chicago, in the county of Cook and State of Illinois, have invented a new, original, and ornamental Design for a Table, of which the following is a specification, reference being had to the accompanying drawing, forming a part thereof, in which,

Fig. 1 is a perspective view of a table, showing my new design;

Fig. 2 is an end elevation thereof; and
Fig. 3 is a side elevation thereof.

I claim:

The ornamental design for a table, as shown.
JEROME L. METZ.
